(57) **CLAIM**

The ornamental design for a distribution component enclosure, as shown and described.

DESCRIPTION

FIG. 1 is a top and front perspective view of a distribution component enclosure showing my new design;

FIG. 2 is a front elevational view thereof;

FIG. 3 is a top plan view thereof;

FIG. 4 is a bottom plan view thereof;

FIG. 5 is a top and front perspective view thereof, showing the upper portion of the enclosure;

FIG. 6 is a front elevational view thereof, showing the upper portion of the enclosure;

FIG. 7 is a top plan view thereof, showing the upper portion of the enclosure;

FIG. 8 is a bottom plan view thereof, showing the upper portion of the enclosure;

FIG. 9 is a top and front perspective view thereof, showing the lower portion of the enclosure;

FIG. 10 is a bottom and front perspective view thereof, showing the lower portion of the enclosure;

FIG. 11 is a top plan view thereof, showing the lower portion of the enclosure;

FIG. 12 is a front elevational view thereof, showing the lower portion of the enclosure;

FIG. 13 is a vertical cross-sectional view thereof showing the lower portion of the enclosure, taken along line 13—13 of FIG. 11; and,

FIG. 14 is a bottom plan view thereof, showing the lower portion of the enclosure.

The lower portion of the enclosure is omitted for clarity of illustration in views of the upper portion, the upper portion is omitted for clarity of illustration in views of the lower portion, and the broken-line disclosure of various elements in the view are for illustrative purposes only and form no part of the claimed design.
